(57) CLAIM

I claim the ornamental design for a vehicle console liner, as shown and described.

DESCRIPTION

FIG. 1 is a perspective view showing my new design for a vehicle console liner;

FIG. 2 is a front elevation view thereof;

FIG. 3 is a rear elevation view thereof;

FIG. 4 is a top plan elevation view thereof;

FIG. 5 is a bottom plan elevation view thereof;

FIG. 6 is a left-side elevation view thereof;

FIG. 7 is a right-side elevation view thereof; and,

FIG. 8 is a top plan view thereof, shown on an exemplary vehicle console.

The broken line showing of the vehicle console is provided for the purpose of illustrating environmental structure and form no part of the claimed design.
